HEEL KNITTING MACHINE

Fritz Lambach, Fairview, N. J., assignor to Robert Reiner, Inc., Weehawken, N. J.

Application December 17, 1938, Serial No. 246,370

15 Claims. (Cl. 66—82)

The present invention relates to the manufacture of hosiery and, more particularly, to an improved flat or full-fashioned knitting machine adapted to knit heel tabs directly into a combination leg and foot stocking blank, and to an improved method of knitting heel tabs into such a blank.

It is the principal object of the invention to provide mechanism capable of knitting heel tabs simultaneously and in opposite directions as continuations of the high heel sections of a combination leg and foot blank and, during the knitting of said heel tabs, of transferring loops of the sole sections of said blank for interlooping connection with the loops at the inner selvedges of the heel tabs, and of transferring certain loops at the outer selvedges of said heel tabs to narrow and shape the same.

Heretofore, because of the standard construction and operation of known knitting machines, it has been customary in knitting heel tabs into a combination leg and foot blank, to lay the yarns by means of yarn carriers operating simultaneously in the same direction and, during the knitting of said courses, to transfer by means of transfer point combs, loops of the first course of each sole section into engagement with the loops at the inner selvedge edge of a completed course of each heel tab. However, it has been found that in such a mode of operation, one or the other of the carriers unavoidably remains in the way of the transfer points, thus interfering with the proper operation of the latter.

Therefore, it is an important object of the present invention to provide mechanisms functioning to operate the carriers in such a manner that the yarns intended to form the heel tabs are laid simultaneously in opposite directions, and to operate the transfer points at every other course when the carriers have reached the outer selvedge edges of the heel tabs so that said points may operate without interference.

It is also among the main objects of the invention to provide correlated mechanisms operable to knit heel tabs simultaneously in opposite directions as continuations of the high heel sections of a combination leg and foot blank, to transfer the marginal loops of the sole sections of said blank for overlapping, interlooping connection with certain loops at the inner selvedges of every other course of said heel tabs, and to transfer certain loops at the outer selvedges of said heel tabs to narrow and shape the same, said mechanisms being respectively associated to co-function in predetermined timed relation.

Another important object of the invention resides in the provision of mechanisms adapted to knit heel tabs into a combination leg and foot blank by knitting simultaneously in opposite directions the heel tabs directly onto the leg portion of the blank, and interknit the selvedge edges of every other course of the heel tabs into the adjoining portion of the foot fabric to form a finished blank.

The invention is moreover characterized by the fact that the mechanical realization thereof may be had through a novel combination of parts easily and readily adapted to operate with an ordinary well known footer knitting machine, without necessitating material changes in the basic construction and operation thereof.

It is also a characteristic feature of the invention to provide a simplified arrangement of co-related mechanisms which may be conveniently and easily combined with a standard footer knitting machine for converting the same into a heeling machine embodying knitting elements operable simultaneously and in opposite directions for effecting the knitting of heel tabs and interknitting overlapping connections between said heel tabs and adjoining portions of the leg blank.

With these and other objects in view, as may hereinafter appear, the several features of the invention and the advantages to be obtained thereby will be readily understood by those skilled in the art from the following description taken in conjunction with the accompanying drawings, in which:

Figure 1 is a front elevation of a portion of a full-fashioned knitting machine embodying the invention.

Figure 2 is an enlarged transversal section through a part of the machine illustrating in side elevation the Coulier motion and elements associated therewith.

Figure 3 is an enlarged detailed section of one of the knitting sections of the machine.

Figure 4 is a sectional view similar to Figure 2, the section being taken through another part of the machine, and illustrating various motion mechanisms thereof.

Figure 5 is an enlarged detail in front elevation of the loop manipulating mechanism of the knitting machine.

Figure 6 is a section taken on line 6—6 of Figure 5.

Figure 7 is a detail of a portion of the loop transfer motion mechanism viewed from the top with certain parts broken away.

- 20 Figure 14 diagrammatically illustrates the high heel, sole, and heel sections of the stocking blank after the knitting of a number of heel courses.
- Figure 15 is a diagrammatic representation of a completed foot and leg stocking blank with the heel tabs knitted into the blank.
- 25 Having more particular reference to the drawings, wherein like characters of reference will designate corresponding parts throughout, it is to be understood that I have shown only those parts of a full-fashioned hosiery knitting machine which are essential to the clear understanding of the present invention. The basic structure of the knitting machine itself, as reproduced in the drawings, is that of the commonly used "Reading" full-fashioned footer with which anyone skilled in the art is well acquainted.
- 30 In the drawings illustrating the preferred construction of the improved knitting machine, the usual machine frame is indicated at 20 and carries a center bed 22 about which are mounted a plurality of spaced knitting sections, designated in their entirety for convenience herein by the reference character 24 (Figure 3).
- 35 Each knitting section 24 essentially comprises a needle bar 26, knock over bits 28, and sinkers and dividers 30. The thread or yarn is fed to the knitting sections 24 by means of carriers 32 depending from the carrier rods 34 mounted for reciprocation in the carrier rod brackets 36.
- 40 The needle bar 26 carries the needles 38 divided into three groups, that is, two end groups 39 and an intermediate group 39' (Figure 5). The needles on the end groups 39 are adapted to receive the yarn from the carriers 32 and act to knit the fabric, whereas the needles in the intermediate group 39' are non-knitting, and serve only to retain the loops of a previously knitted fabric for the purpose to be explained in detail hereinafter.
- 45 Disposed for cooperation with a predetermined number of needles in the knitting needle groups 39 at the opposite ends of the needle bar are two relatively small narrowing combs 40 and 42 respectively fixed to separate narrowing bars 44 and 46 slidably mounted in the usual brackets 47, whereas arranged for coaction with the non-knitting needle group 39' are two relatively wide loop transfer combs 48 and 50 likewise relatively secured to separate narrowing bars 52 and 54 which are also slidably mounted in said brackets 47.
- 50 The narrowing combs 40 and 42 are intended to operate independently of the loop transfer combs 48 and 50 and, for that purpose, two separate and distinct mechanisms are utilized. One mechanism, which may be the usual well

known narrowing mechanism, is operatively associated with the narrowing bars 44 and 46 to impart a longitudinal sliding movement thereto, while the other mechanism, which has been devised especially to control the loop transfer mechanism, is associated with the bars 52 and 54 to impart a longitudinal reciprocating movement thereto.

5 As shown in Figure 1, the narrowing motion mechanism comprises a pair of narrowing nuts 10 56 and 58 respectively engaged with a double threaded spindle 60 rotatably carried on the machine frame so that, upon rotation of said spindle, the narrowing nuts will travel in opposite directions, as indicated by arrows A and B. Each 15 narrowing nut is provided with a flange 62 engageable with stops 64 on the narrowing bars 44 and 46. In this manner, it will be understood that said narrowing bars 44 and 46, with their 20 narrowing combs 40 and 42, will follow the movement of the corresponding narrowing nuts when the spindle 60 is rotated during a narrowing cycle of the knitting machine. During such cycle, the rotation of the spindle is accomplished automatically through actuation of a pawl and ratchet device 66 operated in the usual well known manner.

The transferring motion mechanism comprises a cam disc 68 having camming faces 70 on both of its sides and mounted for oscillation on a 30 rotating shaft 72 suitably fixed in brackets 73. Disposed for riding engagement with the camming faces 70 of the cam disc 68 is a pair of fingers 74 carried by sleeves 76 slidably mounted on the shaft 72, each sleeve being provided with a 35 forked extension 80 engaging a second shaft 82 also suitably fixed in the supporting brackets 73 and adapted to guide said sleeves in their sliding movements. The sleeves 76 are further provided with projections 84 engageable with adjustable 40 stop elements 86, one of said elements being secured to the transfer bar 52 and the other element being secured to the transfer bar 54. The fingers 74 are constantly urged into riding engagement with the camming faces 70 of the cam disc 68 by means of springs 88 conveniently connected to the bars 52 and 54 and to parts of their supporting structures, such as the brackets 47.

The cam disc 68 is actuated by means of a link arrangement consisting of pivoted levers 90 connected to an arm 92 of a sleeve 94 rotatable on the transfer mechanism supporting shaft 95. The sleeve 94 is formed with a second arm 96 connected to a rod 98 in turn connected to one arm 100 of a bell crank lever 102 arranged for oscillation on the back narrowing shaft 104 of the machine frame. The other arm 106 of the bell crank lever 102 is attached to a rod 108 pivoted to a rocking lever 110 carrying a roller 112 disposed for coaction with a pattern cam 114 on the main cam shaft 116 in the manner to be described more fully hereinafter.

Because of this construction, it will be understood that, upon oscillation of the cam disc 68, the transfer bars 52 and 54 will be caused to move 65 in opposite directions, as indicated by the arrows C and D in Figure 5.

The elements so far described receive their motion from the parts of the machine which will now be described.

70 As illustrated in the drawings, the main cam shaft 116 supported in bearings on the machine frame 20 carries in addition to the pattern cam 114 a needle presser cam 118, a needle bar cam 120, a narrowing head actuating cam 122 at each 75

end of the machine, a narrowing dip cam 124, shogging cams 128 and a face cam 130 for preventing operation of the narrowing mechanism.

The needle presser cam 118 operates a follower 132 on a rocker arm 134 and a needle bar fork 136 to impart the usual longitudinal movement to the needle bar. The needle bar follower 138 on a cam lever 139 is operated by the needle bar cam 120 to turn the needle bar lifting shaft 140 which transmits motion through a needle bar lifting arm 142 and bracket 144 to the needle bar, thereby giving the latter its usual lifting movement.

The shogging cams 128 are operated in the usual manner to shift the cam shaft 116 longitudinally or axially in opposite directions. In one shifting position of the cam shaft, the needle presser cam 118 and the needle bar cam 120 are in active relation to their respective followers 132 and 138 to operate the needles for knitting, and each narrowing head actuating cam 122 is in inactive relation with a follower 148, whereby no narrowings are effected. Conversely, in the other shifted position of the cam shaft, the needle presser cam 118 and the needle bar cam 120 are in inactive relation to the followers 132 and 138 whereby no knitting takes place when each narrowing head actuating cam 122 is in active relation to its follower 148 to produce narrowings, and thus shape the fabric being knitted.

Each narrowing head actuating cam follower 148 is mounted on a lever 150 pivotally mounted at one end of the machine frame and pivotally connected by a pin 152 onto the lifting lever 154 adapted to operate the narrowing mechanism by means of the ratchet device 66.

It is to be understood that this mechanism is that usually provided on the knitting machine for variably moving the narrowing combs of each section towards and away from each other to operate the narrowing points thereof, and to vary the travel of the carrier rods supporting the yarn carriers in the usual manner, the ordinary end stops 154 being provided for that purpose.

In accordance with the present invention, and as clearly shown in Figure 3, the jacks 155 for actuating the sets of sinkers associated with the knitting needle groups 39 are operated by separate slur cams 156 and 158 respectively carried by slur cock boxes 160 and 162 individually connected to slur cock bars 164 and 166.

One slur cock bar 164 is rigidly connected through a bracket 168 to the long arm 170 of the Coulier motion mechanism 172 to receive a longitudinal reciprocating movement therefrom. The remaining slur bar 166 is operatively connected to the first mentioned slur cock bar 164 by means of gearings 174 operable to transmit motion to said remaining slur cock bar 166 in a direction opposite to the slur cock bar 164 connected with the long arm 170 of the Coulier motion 172. The gearings 174, as shown in the drawings, preferably consist of a rack 176 affixed to the slur cock bar 164, a rack 178 affixed to the slur cock bar 166, and a pinion 180 supported by means of a bracket 182 mounted upon the center bed 22 of the machine frame. The bracket also preferably carries rollers 184 and 185 respectively disposed to engage the slur cock bar 164 and 166 to assure proper engagement of the racks 176 and 178 with the pinion 180.

Also in accordance with the invention, the carrier bars 34 supporting the yarn carriers 32 associated with the knitting needle groups 39 to feed yarn thereto, are individually connected to sepa-

rate friction boxes 186 and 187 respectively mounted on separate friction rods 188 and 189. One friction rod 188 is connected by means of a bracket 168 to the long arm 170 of the Coulier motion to receive longitudinal reciprocating movement therefrom. The other friction rod 189 is operatively connected to the friction rod 188 by means of gearings 190 operable to transmit motion to said rod 189 in a direction opposite to that of the rod 188. The gearings 190, as shown in the drawings, particularly Figures 8 and 10 thereof, consist of a rack 192 rigidly secured to the friction rod 188, a rack 194 rigidly secured to the friction rod 189, and a pinion 196 suitably supported between the racks 192 and 194 for engagement therewith. The gearings 190 may be enclosed in a housing 198 suitably mounted on the machine frame.

From the foregoing description of the slur and yarn feeding mechanisms, it will be appreciated that, with actuation of the Coulier motion mechanism 172, the slur cock 160 and the yarn carrier 32 associated with one of the knitting needle groups 39, and the slur cam 162 and the yarn carrier 32 associated with the other knitting needle group 39, are caused to move in unison towards and away from each other, thus laying the yarns and actuating the sinkers simultaneously in opposite directions during the knitting cycles of the machine. In this manner, it will be appreciated that, at every other course knitted on the knitting needle groups 39, the carriers become positioned at the outer ends of the needle bar and, accordingly, are moved away from the loop transfer combs 48 and 50 which may then operate without interference during the loop transferring cycles of the machines.

The operative change of the machine to and from the knitting and loop transferring cycles is accomplished automatically by means of a pattern control mechanism, designated in its entirety for convenience herein by the reference character 200. This mechanism 200 is of the usual well known construction and includes the pattern chain 202 provided with a series of buttons, the function of which controls the mechanism to cause the shifting of the main cam shaft 116. The shifting of the main cam shaft brings the narrowing dip cam 124 in position for engagement with a follower 204 carried by the lever system 206 to impart to the entire loop engaging and laterally transferring mechanism its dipping motion. The shifting of the main cam shaft also brings the pattern cam 114 in position for cooperation with the follower 112 to actuate the transfer bars 52 and 54 in the manner hereinbefore stated.

Although the shifting of the main cam shaft causes the dipping motion of the loop engaging and laterally transferring mechanism, and causes the actuation of the transfer rods 52 and 54, the narrowing motion mechanism remains inoperative because it is necessary that the follower 148 be also shifted in order that said narrowing motion mechanism may operate. For that purpose, the pattern chain 202 is provided with a second set of buttons acting on a lever 208 connected to a link arrangement 210 cooperating with the face cam 130 to slide a rod 212 having a forked member 214 connected thereto, which engages the follower 148 to shift the same to a position for riding engagement with the cam 122, whereupon the narrowing motion mechanism operates in the manner hereinbefore stated to actuate the narrowing rods 44 and 46.

From the foregoing, it will be appreciated that the loop transfer mechanism may operate when the narrowing mechanism is idle, or that both mechanisms may operate simultaneously.

5 As hereinbefore stated, the machine is devised to knit heel tabs into a combination full-fashioned leg and foot blank. Such a blank has been shown in Figure 11. As shown in Figure 11, the blank 220 comprises a leg 222 having reinforced high heel portions 224 and a foot 228 having reinforced sole portions 226 which are formed by continuous knitting into the combination leg and foot blank.

Between the leg and foot portions of the blank, 15 as best shown in Figure 12, two partial non-reinforced courses 238 are provided which serve to form a line of demarcation between those portions of the last course of the foot fabric and the first course of the sole fabric into which the heel 20 portions are subsequently to be knitted. During the knitting of the partial courses referred to, the knitting with a reinforced yarn is continued on a restricted number of needles so that a reinforced selvedge loop 232 is provided at the 25 inner ends of the partial non-reinforced connecting courses 238 to form the heel corner of the finished blank.

It will be understood that the courses 238 may be knitted with a separate yarn so that when 30 these connecting loops are subsequently removed, as by cutting or pulling out the yarn forming these loops, no yarn forming the body portion of the fabric will have been broken or cut.

In accordance with the invention, the last 35 course of the leg fabric loops, designated at 234, and the first course of reinforced sole fabric loops, designated at 236, together with the selvedge loops 232, are topped onto a series of topping points comprising a stationary point 238 and two additional point sections, designated 40 respectively at 240 and 242, which are arranged in parallel relationship, as shown in the diagrammatic Figure 12, that is, in substantially the same positions in which the fabric loops appear in the 45 combination blank.

It will be noted that the topping operation, as described, is carried out prior to the cutting or removal of the partial non-reinforced courses 238 so that when the high heel and sole portions 50 of the fabric are separated, all of the disengaged fabric loops are supported by the topping points to prevent any possibility of dropping the loops.

In accordance with the preferred form of applicant's method, the loops forming the partial courses 238 may be severed by means of a cutting knife 244 to permit the separation of the two parallel topping point sections and the loops supported thereon, which are then moved outwardly 55 into a straight line relationship in which all of the points are spaced to register with the quills of a transfer bar, which may be of the ordinary description and utilized for transferring the fabric loops from the topping points to the needles of a heel knitting machine, as represented 60 in Figure 13.

In knitting the heel portions, the carriers 32 are actuated simultaneously and in opposite directions to lay the yarns across the active knitting needles so as to knit the courses 248 (Figure 14) of the heel portions 250. During the knitting of said heel portions, the loops 238 of the first courses of the sole portions 236 are gradually transferred from interknitted engagement with the heel tabs by operation of the loop transfer mechanism already described.

The heel tabs 250 may be shaped through operation of the narrowing mechanism functioning to actuate the narrowing combs 40 and 42, as previously explained.

It is to be understood that the mechanical construction of the several parts herein shown and described is capable of certain modifications and, therefore, any modification coming within the scope of the subjoined claims is to be considered within the spirit of the invention. 10

What I claim is:

1. In a knitting machine of the character described, two end sets of knitting needles and an intermediate set of non-knitting needles adapted to have knitted fabric portions topped thereon; means for laying yarns simultaneously in opposite directions for the knitting of courses as continuations of the fabric portions topped on the knitting needles; and means for interknitting the loops of the fabric portions topped on the non-knitting needles with certain loops of said courses during the knitting thereof. 15

2. In a knitting machine of the character described, two end sets of knitting needles and an intermediate set of non-knitting needles adapted to have knitted fabric portions topped thereon; means for laying yarns simultaneously in directions towards and away from each other for the knitting of courses as continuations of the fabric portions topped on the knitting needles; and means for interknitting the loops of the fabric portions topped on the non-knitting needles with certain loops of said courses after the knitting thereof from the yarns laid in directions away from each other. 25

3. In a knitting machine of the character described, two end sets of knitting needles and an intermediate set of non-knitting needles adapted to have knitted fabric portions topped thereon; means for forming courses simultaneously and in opposite directions upon said end sets of knitting needles; and sets of transfer combs associated with the non-knitting needles and operable to pick up the loops from said non-knitting needles and transfer said loops onto certain of the 40 knitting needles. 45

4. In a knitting machine of the character described, two end sets of knitting needles and an intermediate set of non-knitting needles adapted to have knitted fabric portions topped thereon; means for forming courses simultaneously and in opposite directions upon said end sets of knitting needles; sets of transfer combs associated with the non-knitting needles and operable to pick up the loops from said non-knitting needles and transfer said loops onto certain of the knitting needles; and means for controlling the transfer movement of said sets of combs for actuation thereof when said forming means have formed courses in directions away from each other. 55

5. In a knitting machine of the character described, two end sets of knitting needles and an intermediate set of non-knitting needles adapted to have fabric portions topped thereon; means for laying yarns simultaneously in opposite directions for the knitting of courses as continuations of the fabric portions topped on the knitting needles; means for transferring the loops from the non-knitting needles onto certain of the knitting needles for interknitting said loops with certain loops of said courses during the knitting thereof; and means associated with a number of knitting needles for transferring the loops thereon to narrow certain of said courses. 65

6. In a knitting machine of the character described, two end sets of knitting needles and an intermediate set of non-knitting needles adapted to have knitted fabric portions topped thereon; 5 means for laying yarns simultaneously in directions towards and away from each other for the knitting of courses as continuations of the fabric portions topped on the knitting needles; means for transferring the loops from the non- 10 knitting needles onto certain of the knitting needles for interknitting said loops with certain loops of said courses after the knitting thereof from the yarns laid in directions away from each other; and means associated with a number of 15 knitting needles for transferring the loops thereon to narrow certain of said courses.
7. In a knitting machine for knitting a pair of heel tabs into a combination leg and foot stocking blank by knitting said tabs to corresponding course portions in the blank and successively transferring loops of other course portions in the blank to loops of said heel tabs as the knitting thereof progresses, the combination 20 of loop forming and positioning mechanism comprising transfer point means and a loop manipulating implement structure including two end sets of knitting needles and an intermediate set of non-knitting needles, the loops of the first mentioned course portions to be topped onto the sets 25 of knitting needles, and the loops of the second mentioned course portions to be topped onto the intermediate set of non-knitting needles; and means for actuating and controlling said loop forming and positioning mechanism providing for 30 the formation of loops simultaneously and in opposite directions on the end sets of knitting needles, and transferring loops from the intermediate set of non-knitting needles to loops formed on the end sets of knitting needles.
8. In a knitting machine for knitting a pair of heel tabs into a combination leg and foot stocking blank by knitting said tabs to corresponding course portions in the blank, and successively transferring loops of other course portions in the blank to loops of said heel tabs as the knitting thereof progresses, the combination 40 of loop forming and positioning mechanism comprising transfer point means and a loop manipulating implement structure including two end sets of knitting needles and an intermediate set of non-knitting needles, the loops of the first mentioned course portions to be topped onto the sets of knitting needles, and the loops of the second mentioned course portions to be topped onto the intermediate set of non-knitting needles; and means for actuating and controlling said loop forming and positioning mechanism providing for 45 the formation of courses simultaneously towards and away from each other and for narrowing on said end sets of knitting needles and transferring loops from the intermediate set of non-knitting needles onto loops of the courses formed on the end sets of knitting needles after 50 said courses have been formed away from each other.
9. In a knitting machine for knitting a pair of heel tabs into a combination leg and foot stocking blank by knitting said heel tabs to corresponding course portions in the blank and successively transferring loops of other course portions in the blank to loops of said heel tabs as the knitting thereof progresses, the combination 55 of loop manipulating and fashioning mechanism comprising transfer point means, narrowing point means, and a loop manipulating implement structure including two end sets of knitting needles and an intermediate set of non-knitting needles, the loops of the first mentioned course portions to be topped onto the sets of knitting needles and the loops of the second mentioned course portions to be topped onto the intermediate set of non-knitting needles; and means for actuating and controlling said loop manipulating and fashioning mechanism providing for the formation of loops simultaneously and in opposite directions for the knitting of courses onto said sets of knitting needles; and means for transferring loops from said non-knitting needles to the inner selvedge loops knitted by the knitting needles and causing the transferred loops to be interknitted with said selvedge loops.
10. In a knitting machine for knitting a pair of heel tabs into a combination leg and foot stocking blank by knitting said heel tabs to corresponding course portions in the blank and successively transferring loops of other course portions in the blank to loops of said heel tabs as the knitting thereof progresses, the combination 60 of loop manipulating and fashioning mechanism comprising transfer point means, narrowing point means, and a loop manipulating implement structure including two end sets of knitting needles and an intermediate set of non-knitting needles, the loops of the first mentioned course portions to be topped onto the sets of knitting needles, and the loops of the second mentioned course portions to be topped onto the intermediate set of non-knitting needles; and means for actuating and controlling said loop manipulating and fashioning mechanism providing for the formation of courses simultaneously towards and away from each other and for narrowing on said end sets of knitting needles and transferring loops from the intermediate set of non-knitting needles onto loops of the courses formed on the end sets of knitting needles after 65 said courses have been formed away from each other.
11. In combination, in a straight knitting machine, a needle bar; two end sets of needles on the bar to receive series of yarn loops to which further loops are to be knitted; a set of non-knitting needles also on said bar to receive other series of yarn loops; mechanism including means for laying yarns simultaneously and in opposite directions for the knitting of courses onto said sets of knitting needles; and means for transferring loops from said non-knitting needles to the inner selvedge loops knitted by the knitting needles and causing the transferred loops to be interknitted with said selvedge loops.
12. In combination, in a straight knitting machine, a needle bar; two end sets of needles on the bar to receive series of yarn loops to which further loops are to be knitted; a set of non-knitting needles also on said bar to receive other series of yarn loops; mechanism including means for laying yarns simultaneously and in directions 70 towards and away from each other for the knitting of courses onto said sets of knitting needles; and means for transferring loops from said non-knitting needles to the inner selvedge loops knitted by the knitting needles and causing the transferred loops to be interknitted with said selvedge loops after said courses have been knitted from the yarns laid away from each other.
13. In combination, in a straight knitting machine, a needle bar; two end sets of needles on the bar to receive series of yarn loops to which further loops are to be knitted; a set of non-knitting needles also on said bar to receive other series of yarn loops; mechanism including means 75

- for laying yarns simultaneously and in opposite directions for the knitting of courses onto said sets of knitting needles; and means for transferring loops from said non-knitting needles 5 to the inner selvedge loops knitted by the knitting needles, causing the transferred loops to be inter-knitted with said selvedge loops and including transfer bar means and a cam for operation transversely to the transfer bar means to 0 impart simultaneous transfer movement thereto in opposite directions.
14. In combination, in a straight knitting machine, a needle bar; two end sets of needles on the bar to receive series of yarn loops to which further loops are to be knitted; a set of non-knitting needles also on said bar to receive other series of 5 yarn loops; mechanism including means for laying yarns simultaneously and in opposite directions for the knitting of courses onto said sets of 10 knitting needles; means for transferring loops from said non-knitting needles to the inner selvedge loops knitted by the knitting needles and causing the transferred loops to be interknitted 15 20

with said selvedge loops; and narrowing means to transfer inwardly outer selvedge loops of said courses.

15. In combination, in a straight knitting machine, a needle bar; two end sets of needles on the bar to receive series of yarn loops to which further loops are to be knitted; a set of non-knitting needles also on said bar to receive other series of 5 10 15 20 yarn loops; mechanism including means for laying yarns simultaneously and in opposite directions for the knitting of courses onto said sets of knitting needles; means for transferring loops from said non-knitting needles to the inner selvedge loops knitted by the knitting needles, causing the transferred loops to be interknitted with said selvedge loops and including transfer bar means and a cam for operation transversely to the transfer bar means to impart simultaneous transfer movement thereto in opposite directions; and narrowing means to transfer inwardly outer selvedge loops of said courses.

FRITZ LAMBACH.
